UNITED STATES PATENT OFFICE.

HENRY S. BREWINGTON, OF BALTIMORE, MARYLAND.

BOTTLE-STOPPER.

SPECIFICATION forming part of Letters Patent No. 691,107, dated January 14, 1902.

Application filed October 24, 1901. Serial No. 79,809. (No model.)

To all whom it may concern:

Be it known that I, HENRY S. BREWINGTON, a citizen of the United States, residing in the city of Baltimore, in the State of Maryland, 5 have invented certain new and useful Improvements in Bottle-Stoppers, of which the following is a specification.

This invention relates to bottle-stoppers of that class in which a sheet-metal cap and a suitable packing placed in the same is applied over the mouth of the bottle, the object of the invention being to supply a cheap sealing device or closure for bottles by which the bottles can be hermetically sealed, so as to 15 prevent the escape of gas from the bottle, and which can be attached to the bottle in a quick and convenient manner and removed from the same by one of the well-known bottle-openers; and for this purpose the invention 20 consists of a bottle-stopper comprising a cap provided with an external circumferential corrugation or groove and forming an internal annular bead or shoulder below its top, a packing-disk placed in said cap and 25 retained by said bead, and a depending cylindrical portion below said bead, said cylindrical portion being adapted to be applied to an annular exterior shoulder on the neck of 30 the bottle, as will be fully described herein- after and finally pointed out in the claims.

In the accompanying drawings, Figure 1 represents a perspective view of a cup-shaped blank used for the caps of my improved bottle-stopper. Fig. 2 is a vertical central section of the same. Fig. 3 is a perspective view of the cap provided with a circumferential corrugation for retaining the packing-disk in the same. Fig. 4 is a vertical central section of Fig. 3. Figs. 5 and 6 are vertical transverse sections showing my improved stopper, respectively, as placed in position over the bottle-neck and after being applied to the same; and Fig. 7 is a side elevation of my improved bottle-stopper shown in position on the bottle-neck.

Similar letters of reference indicate corresponding parts in the different figures of the drawings.

Referring to the drawings, *a* represents the 50 neck of a bottle, which is provided with an annular exterior shoulder or rim *a'*, a groove *b* below said shoulder or rim, and a larger

bulge *b'* below the groove, as shown clearly in Figs. 5 and 6.

The stopper consists of a cap *d*, of suitable 55 sheet metal, the blank *d'* of which is made in the shape of an inverted cup, as shown in Figs. 1 and 2. Into the cup-shaped blank *d'* is inserted a packing-disk *e*, of cork or other suitable elastic material. The packing-disk 60 *e* is made cylindrical in shape and retained in the cup-shaped blank *d'* by pressing an external circumferential corrugation, forming an internal annular bead *d*² at a short distance from the top of the blank, into the same, said 65 bead retaining the packing-disk *e* by compressing the circumference of the same, so as to prevent thereby the dropping or detaching of the packing-disk from the cap before it is applied to the bottle. Below the bead 70 *d*² a depending cylindrical portion *d*³ is formed in the cap, which serves for the purpose of attaching the same to the annular exterior shoulder or rim *a'* on the bottle-neck. This is accomplished by placing the cap with the 75 packing-disk over the mouth of the bottle in such a manner that the circumferential corrugation or bead, together with the packing-disk, rest on the top of the bottle-neck, as shown in Fig. 5. When the cap and pack- 80 ing-disk are in this position, the depending cylindrical portion of the cap is attached to the annular exterior shoulder or rim on the bottle-neck by inwardly compressing its lower edge, so as to produce a tight fit on the lower 85 part of the rim, as shown in Fig. 6. Simultaneously a downward pressure is exerted on the top of the cap, so that the thickness of the upper portion above the bead and the thickness of the packing-disk in the same is 90 reduced, the lower surface of the packing-disk tightly applied to the top of the bottle-neck, while the under side of the packing-disk projects somewhat into the mouth of the bottle. By the tight application of the pack- 95 ing-disk to the top of the neck of the bottle the hermetical sealing of the bottle is obtained by the tight compression of the packing-disk, so that the liquid in the bottle is prevented from passing through or around the disk and corroding the inner surface of the cap. When the cap is thus applied to the bottle-neck, it has a neat appearance from 100 the outside, as there are no projecting edges

of any kind which can catch, so as to produce the accidental removal of the cap from the bottle.

Any-approved bottle-opener can be used for opening my improved bottle-stopper by engaging the inwardly compressed or spun lower edge of the cap, said lower edge giving a sufficient hold to the bottle-opener for being readily removed whenever the bottle is to be opened.

Having thus described my invention, I claim as new and desire to secure by Letters Patent—

1. The combination, with a bottle-neck provided with an exterior annular shoulder at its edge and a groove below the same, of a sealing-cap having an external circumferential corrugation which forms an interior annular bead, and having a depending cylindrical portion below said bead adapted to fit around said exterior annular shoulder of the bottle-neck, and its lower edge compressed into said groove, and a packing-disk retained

in the upper portion of the cap above said internal bead, the upper and lower walls of the corrugation being separated when the cap is affixed to the bottle, substantially as set forth.

2. The combination, with a bottle-neck provided with an exterior annular shoulder, of a sealing-cap having an external annular corrugation forming an internal annular bead and also having a depending cylindrical portion below said bead compressed inwardly below the shoulder of the bottle, and a packing-disk retained in the upper portion of the cap above the bead, the upper and lower walls of the corrugation being separated when the cap is affixed to the bottle, substantially as set forth.

In testimony that I claim the foregoing as my invention I have signed my name in presence of two subscribing witnesses.

HENRY S. BREWINGTON.
